United States Patent Office.

GREENLEAF STACKPOLE, OF NEW YORK, N. Y.

Letters Patent No. 63,438, dated April 2, 1867; antedated March 18, 1867.

IMPROVEMENT IN BIT-BRACES.

The Schedule referred to in these Letters Patent and making part of the same.

TO ALL WHOM IT MAY CONCERN:

Be it known that I, GREENLEAF STACKPOLE, of the city of New York, in the county of New York, in the State of New York, have invented a new and useful Improvement in Bit-Braces; and I do hereby declare the following to be a full, clear, and exact description of the construction and operation of the same, reference being had to the accompanying drawings, and to the letters of reference marked thereon, in which—

Figure 1 is a perspective view of the improvement, with all parts in their proper place, ready to receive a bit.

Figure 2 is a perspective view of the main body of the brace before the ring and jaws are attached.

Figure 3 is a perspective view of the ring.

Figure 4, a perspective view of the jaws.

Figure 5 is a sectional view of the ring and jaws with a bit held in position for use.

Figure 6 is an end view of the main body of the improvement, showing the socket that receives the bit.

Similar letters of reference indicate like parts in all the figures.

A A are spiral slots, starting from points directly opposite each other, and running parallel to each other diagonally about half way around the ring M. B shows the outer end of the jaws extended ready to receive the bit. C shows a projection on the jaws, which passes out through the slot A A; so that by turning the ring M the jaws may be thrown out or drawn in on a line with the bit. D is a slot that guides and keeps them on a line with the bit. H is a shoulder, against which the inner end of the ring rests when the parts are together in their proper places. F F are recesses forming shoulders that are made to press against the outer end of the ring, and hold it in its place by driving a wedge into the socket G, and spreading it after the ring and jaws have been slipped into their places. A A are the slots as seen before the ring is slipped on or connected to the other parts. Fig. 4 shows the jaws separated from the other parts, and shows the projections C C, which pass through the slots in the ring when the parts are together, as shown in fig. 1. Fig. 5 shows a taper on the inside of the ring, making it smaller at the front end, which is for the purpose of causing the jaws to spread as they are moved outward, by pressing their inner ends inward; it also shows the jaws drawn in, holding the bit a. The dotted lines show the jaws extended, ready to receive the bit. In fig. 6 G is the socket, in which the shank of the bit is held. D D is the end of the slots, which guide the jaws on a line with the bit. To tighten the outer ends, B, of the jaws upon the bit a, the ring M must be turned to the left, by which movement the spiral slots A act on the projection C C to draw the jaws inward into the bit-brace, and at the same time close the ends B of the jaws together by the contact of the jaws with the outer end of the ring. To open the jaws the ring M is turned in the opposite direction, and the jaws are moved outward and opened. The opening motion is positive, being induced by the contact of the inner ends, b, of the jaws against the contracting interior of the ring M. The ring M does not move endwise, but simply turns and induces the opening and closing of the jaws by moving the latter endwise. The ring cannot be taken off or lost, neither can the jaws. I prefer to manufacture the parts of malleable cast iron. It allows the socket to be distended successfully to retain the ring and the other parts permanently. The male part B¹ of one jaw is let into the female part B² of the other jaw, as plainly shown in fig. 4, to insure a unity of action or position of the jaws, and to form a firm, reliable, and cheap hinge for the opening and closing motion.

Having thus described my invention, what I claim, and desire to secure by Letters Patent, is—

I claim the bit-brace constructed and operated substantially as herein described.
